CLUTCH-HEAD TORQUE INDICATING
WRENCH

Richard A. Johnson, West Union, Iowa

Application November 22, 1946, Serial No. 711,774

8 Claims. (Cl. 73—139)

1

This invention relates to certain new and useful improvements in socket wrenches of a ratcheting clutch-head type in which a rigid, annular head or annulus on the outer end of an ordinary handle encompasses and substantially embraces a centrally socketed head and wherein the latter is fashioned to carry coating spring-pressed, friction clutch rollers; but has reference in particular to special means which is employed in association with said heads and is adapted to measure and indicate the turning effort or torque required to properly and safely use the wrench in a manner to prevent over-tightening and under-tightening of bolts and nuts, and to thus save against distortion of screw-threads.

More specifically, the invention centers in and is founded upon a carefully perfected instrumentality embodied in workably related, precision balanced mechanical parts characterized, as above mentioned, and including a simple and expedient addition to a somewhat conventionally constructed wrench; said instrumentality functioning to pick up and translate the relative angular movements of said annulus and head to visibly translate the axial rotary movements of said head to an index on the handle, whereby to suitably measure the degree of twisting force required to drive a nut or bolt home, this measurement in relation to the longitudinal axis of said handle.

Briefly and broadly recited, and viewed from a structural standpoint, the disclosure herein embodied has to do with a socket wrench of a clutch-head type comprising an elongated handle having a fixed annular head at one end, a centrally socketed clutch-head confined and mounted for rotation in said annular head and including suitable friction clutch means, and torque indicating and measuring means coacting with the clutch-head and handle to assist a user in ascertaining and determining excessive stresses and strains in a manner to prevent over-tightening of bolts and nuts and to minimize the likelihood of stripping and distorting screw-threads or breakage of the wrench.

Another phase and object of the invention has to do with a friction-type clutch-head wrench for manual use in which the handle, annular head, clutch-head, friction grips and assembling and retaining washers are somewhat old and well known, from a general point of view, the invention itself being extremely simple in that it is characterized by a ring-like member with detents pressed into frictional contact with a clutch-head, said ring-like member being provided with

2

an outstanding tang-like extension functioning as an indicator finger, the same having a scale for coaction with an index fixedly mounted on a simple plate carried by a wrench handle.

6 The general object of the invention is to structurally, functionally and otherwise improve upon wrenches in the category under advisement, this by providing simple, reliable, and practical means whereby it is convenient and possible to measure 10 the degree of twist or torque required and the amount of applied handle-turning force in relation to the load moved, this to attain the ends previously set forth.

Other objects, features and advantages will 15 become more readily apparent from the following description and the accompanying illustrative drawings.

In the drawings, wherein like numerals are 20 employed to designate like parts throughout the same—

Figure 1 is a top plan view, with portions broken away to expose otherwise concealed parts.

Figure 2 is likewise a plan view, this being of 25 a fragmentary type, and certain of the parts being removed to expose the friction-type clutch-head.

Figure 3 is a fragmentary sectional view, this being on enlarged scale and serving to bring out 30 the complete assembled parts in proper mechanical relationship.

Figure 4 is a perspective view of the clutch-head per se.

Figure 5 is a perspective view of the principle 35 part of the invention, the clutch-head motion pickup, translating and indicator unit.

Figure 6 is a section on the line 6—6 of Figure 5, looking in the direction of the arrows.

Referring now to the drawings by distinguishing 40 reference numerals, it will be seen that the handle means is broadly denoted at A, the clutch-head, or "headed-clutch," as it is sometimes referred to in the art, is indicated at B and that the principal part or unit forming the major 45 feature in the measuring instrumentality is indicated at C (see Figs. 5 and 6).

The handle means A comprises a suitable handle 8 with a fixed annular head 9 at its outer end. The head on one side, which we may conveniently call the bottom, is formed with a recess 9a in which an assembling washer or plate 10 is seated, as shown in Figure 3. Fitted into the surrounding annulus or annular head 9 is the clutch-head B, this being in the form of a body (see Fig. 4) having a central tool and work socket 11 and being provided with marginal, equi-

distant, circumferentially spaced notches or pockets 12 to accommodate friction clutch rollers 13 pressed against the inner periphery of the annular head 9 by way of coiled springs 14. Also confined within the limits of the annular head 9 is another assembling washer 15 (see Fig. 3) and outwardly of this is a third cover-forming and facing washer 16, said several washers being bolted in place by bolts 17 and said bolts serving to thus group and assemble all of the parts which go to make up the clutch-head unit or assembly.

The measuring unit C, comprises an annulus or ring 18 of metal or the like, the same having indentations 19 at circumferentially spaced points, said indentations forming springy detents and bearing frictionally against the adjacent outer surface of the washer 15, as shown in Figure 3. The annulus 18 is provided with a tang-like extension 20, which may be conveniently identified as an indicator or indicating finger. This finger is in spaced parallelism to said handle 8 and provided, adjacent its free-swingable and indicating end, with an arcuate slot 21 accommodating a stop-screw 22 threaded into the handle 8. The visible face of the indicator finger is provided with calibrations 23 forming a scale coacting with an index 24 on an index plate 25, the latter bolted in place on the handle as shown in Fig. 1.

By way of introduction to the mode of operation of my wrench, it will perhaps simplify matters if the reader visualizes the scale-carrying torque measuring and indicating means C and clutch-head B as one unit or assembly. However, it is to be remembered that even though means C is bolted and thus frictionally clamped (between 15 and 16) to head B, it nevertheless has limited relative rotary movement to head B. Secondly, the handle 8 plus its annulus 9 and fixed index 24 (part A) may be visualized as a second unit, complementary to said first-named unit.

Now, let us take up the first stage or cycle of operation and assume, in so doing, that the work (nut, bolt, socket, tool or the like) is loose and therefore freely turnable. So, we place the socket 11 of head B on the work (not shown) and, with the roller clutch 12 and 13 means positively locking the annulus 9 to the head B, swing handle 8 clockwise. Visualizing this step, it will be seen that the work, head B, indicator means C and handle means A travel together, that is, in unison. On the return swing or stroke, the head B stays put with the work and the handle means A picks up and swings the indicator means C back to the starting position for a new hold. This action is due to the fact that the stop screw 22 is in abutting contact with the right hand end of slot 21 (see Fig. 1), and also because of the return "slip action" of the ring 18 between washers 15 and 16. Consequently, the means C is responsive to and moves in a clockwise direction with the clutch-head B and handle means A; and is also responsive and moves in a counter-clockwise direction in unison with handle unit or means A while the clutch head B stays put. Thus, we complete one cycle of the operation and, obviously, said cycle is repeated until the work, initially loose and turnable, is now substantially "home" and virtually, but not quite, stationary. In this connection, it will be seen that the index 24 on the handle 8 registers at all times with "zero" on the scale 23.

Assuming, then, that the work is tight, the clutch-head B becomes stationary due to tight-

ening resistance of said work and when further pressure is brought to bear on said handle 8, the clutch rollers 13 ride to final wedging and locking positions in pockets 12. This is the stage when the torque measuring and indicating means becomes significant and comes into play and begins to register, thus to give the desired pounds pressure reading on scale 23. At this stage, finger 20 is now stationary with clutch-head B, and handle 8, together with plate 25 and index 24, continues to move (as the rollers 13 ram and jam into shallow ends of said pockets 12) clockwise, resulting in movement of said index 24 along scale 23 and revealing the desired measurement in stated pounds pressure. As is evident, when index 24 swings across the then stationary scale, the stop screw 22 also rides from right to left in slot 21. The given measurement is noted and mentally retained, and the cycle is repeated, which results in the index 24 moving back to zero for the next new "hold" and take-up step, provided a further measurement has to be taken.

From the foregoing, it is evident that means C is not actuated in response to all movement of the clutch-head B and the surrounding annular head 9 but only to the apparently slight movement permitted by the rollers 13 when the handle 8 is moved in a clockwise direction tending to lock the clutch-head B to the surrounding annular head 9.

The workability and inter-relationship of the parts described results in a sensitive, precision-type ratchet wrench, through the medium of which it is possible to measure the degree of twist, or twisting force which has to be applied to a handle in order to turn the load. It follows that the user is thus provided with a simple and expedient means enabling him to promptly detect an over-strain and thus prevent (1) breakage of the wrench and (2) distorting of coacting threads between a nut and bolt or equivalent assembly.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and within the scope of the appended claims.

What I claim is:

1. A socket wrench of a clutch-head type comprising an elongated handle having a fixed annular head, a centrally socketed clutch-head confined for limited rotation within the confines of said annular head, top and bottom washers on opposite sides of and fastened to said head, a third washer spaced from the top washer and also fastened to said head, a ring-like member interposed movably between the third-named and top washers and including detents frictionally contacting said top washer and further including an extension forming an indicating finger, the latter being parallel to and movable with as well as in relation to said handle.

2. A socket wrench of the clutch-head type comprising a handle having a fixed annular head, a centrally socketed clutch-head confined and mounted for rotation in said annular head, an assembling and retaining washer mounted with-

in the confines of said annular head and being in contact with said clutch-head, a second washer mounted within the confines of said annular head and resting against the opposite face of said clutch-head, a third washer, bolts securing said several washers and clutch-head together in assembled turnable relationship, a ring-like member interposed between the second and third washers and having circumferential bends forming friction detents coacting with the second-named washer, said ring-like member being provided with an extension forming an indicating finger.

3. A socket wrench of the clutch-head type comprising a handle having a fixed annular head at its outer end, a centrally socketed clutch-head confined and mounted for operational rotation in said annular head, an assembling and retaining washer mounted within the confines of said annular head and in contact with one face of said clutch-head, a second washer mounted within the confines of said annular head and resting against the opposite face of said clutch-head, a third washer, bolts securing said several washers and clutch together in assembled simultaneously turnable relationship, a ring-like member interposed for relative rotary movement between the second and third washers and having circumferential bends forming friction detents coacting with the second-named washer, said ring-like member being provided with an extension forming an indicating finger, said indicating finger having a graduated scale, and said handle having a fixed index coactable with said scale.

4. A socket wrench of the clutch-head type comprising a handle having a fixed annular head at its outer end, a socketed clutch-head confined and mounted for rotation in said annular head, an assembling and retaining washer mounted for rotation within the confines of said annular head and being in contact with said clutch-head, a second washer mounted within the confines of said annular head and resting against the opposite face of said clutch-head, a third washer, bolts securing said several washers and head together in assembled turnable relationship, a ring-like member interposed between the second and third washers and having circumferential bends forming friction detents coacting with the second-named washer, said ring-like member being provided with an extension forming an indicating finger, said indicating finger being slotted, said handle being provided with a stop screw and said stop screw being operable in said slot.

5. A socket wrench of the clutch-head type comprising an elongated handle having a fixed annular head at its outer end, a centrally socketed clutch-head confined and mounted for rotation in said annular head, an assembling and retaining washer mounted within the confines of said annular head and being in contact with said clutch-head, a second washer mounted within the confines of said annular head and resting against the opposite face of said clutch-head, a third washer, bolts securing said several washers and head together in unitarily assembled turnable

relationship, a ring-like member interposed between the second and third washers and having circumferential bends forming friction detents coacting with the second-named washer, said ring-like member being provided with an extension forming an indicating finger, said indicating finger being slotted, said handle being provided with a stop screw and said stop screw being operable in said slot, and said finger being provided with a measuring scale, and said handle being provided with a fixed index with which the graduations of the measuring scale coact.

6. A ratcheting - type clutch-head socket wrench of the class shown and described comprising a handle provided with an annular head and further provided at a predetermined point with an index fixed on said head, a work-engaging and turning head mounted for rotation in said annular head, friction clutch means interposed between coacting marginal portions of said heads, a force indicating unit having a portion opposed to said turning head and an indicating finger opposed and parallel to said handle and having a scale with which said index is cooperable, and means for frictionally assembling and clamping said portion against said turning head and permitting said indicating unit to move with as well as relative to said turning head.

7. The structure specified in claim 6 wherein said indicating finger is provided at its outer swingable end with a transverse arcuate slot, and a stop screw is carried by said handle and projects into and through said slot.

8. A ratcheting type dual headed wrench of the class shown and described comprising an annular head provided with a rigid handle, a second head fitted within the confines of said annular head and provided with a work-engaging socket, ratcheting means interposed between peripheral portions of said heads, a ring-like member opposed to one face of said second-named head and having an indicating finger opposed and parallel to said handle, said indicating finger being provided with a transverse arcuate slot and a graduated measuring scale cooperable with the slot, a stop screw mounted in said handle and fitting into said slot, said handle having a relatively fixed index and said index being registrable with the graduations on said scale, a clamping and assembling member connected with said second-named head, said ring member being interposed between the clamping member and said second-named head and movable in conjunction with as well as separately from said last-named head.
